BY ATTORNEY.

UNITED STATES PATENT OFFICE

2,200,701

SCREEN DOOR LATCH

John T. Moore, Dallas, Tex., assignor of thirty
per cent to W. U. Howell, Dallas, Tex.

Application August 11, 1936, Serial No. 95,346
Renewed October 12, 1939

1 Claim. (Cl. 292—20)

This invention relates to fasteners for screen doors, windows, and other openings and it has particular reference to a latch designed to discourage unlawful entry.

5 The principal object of the invention is to provide a latch for doors and screens which requires the use of the hands for operation to effect its detachment from the element to which it is secured in latching a door or screen.

10 Another object of the invention resides in its resiliency as a part of its effectiveness in maintaining its locked relationship with a companion element. Moreover, the construction of the latch requires that it be so manipulated as to rotate its 15 operative end out of its retaining element in order to effect its release therefrom and in view of this requirement, access to the premises from the exterior is rendered difficult.

With the foregoing objects as paramount, the 20 invention has particular reference to its salient features of construction and arrangement of parts which will become manifest as the description proceeds, taken in connection with the accompanying drawing, wherein:

25 Figure 1 is a perspective view of a device constructed according to the present invention.

Figure 2 is a plan view thereof.

Figure 3 is an elevation of an eyelet of the type for receiving the invention.

30 Figure 4 is a slight perspective view showing one end of the latch engaged with the receiving eyelet, and

35 Figure 5 is a side elevation, showing the latch in engaged relation with the eyelet, or in operative position.

Continuing with a more detailed description of the drawing, reference is primarily made to Figure 1 in which is shown a wire, tempered to the desired resiliency and intermediate its ends, a 40 loop 1 is made. The arms or extensions 2 are of equal length and terminate in an upward bend a and a downward bend b, the latter terminataing

in hooks c, turned outwardly at right angles to the axes of the arms or extensions 2.

The hooks c engage the eyelet 3, which is affixed to the jamb 4 (Figure 5) of the door or window, but to effect this engagement, it is necessary to first press the arms or extensions 2 together and rotate them slightly to guide the hooks c into the eyelet. A similar manipulation is necessary to effect release of the latch from the retaining eyelet 3.

An eyelet 5, engaging the loop 1 is screwed into the frame 6 of the door and retains the latch loosely so that it may be oscillated or rotated, as explained previously to effect its engagement with and disengagement from the eyelet 3.

10 It will be understood that the positions of the eyelet 3 and 5 may be reversed so that the latch will be affixed to the jamb rather than to the door frame, if desired. Moreover, it is pointed out that the invention is equally effective as a latch 15 for window screens and similar uses.

20 Manifestly, the construction as shown and described is capable of some modification and such modification as may be construed within the scope and meaning of the appended claim is also 25 considered to be within the spirit and intent of the invention.

I claim:

20 A latch comprising a length of resilient wire having a loop intermediate its ends and having 30 substantially parallel extensions of equal length, the ends of said extensions being bent upward and downward to define inverted V-shaped legs and terminating in hooks, said hooks and downwardly bent legs being arranged to lie in common planes, the planes of the hooks determining 35 planes which are at right angles to the planes determined by the extensions, said V-shaped portions being arranged to spread apart by the resiliency of said wire, and said hooks formed to 40 be received by retaining means for joint secure-
ment.

JOHN T. MOORE.
